United States Patent Office

Des. 198,105
Patented Apr. 28, 1964

198,105

BOTTLE

Patrick J. Ferree, Minneapolis, Minn., assignor to Bemis Bros. Bag Company, Minneapolis, Minn., a corporation of Missouri

Filed Oct. 14, 1963, Ser. No. 76,959

Term of patent 14 years

(Cl. D58—6)

FIG. 3.

FIG. 1.

FIG. 2.

FIG. 4.

FIG. 1 is a perspective view of a bottle showing my new design;

FIG. 2 is a view in elevation of the other face of the bottle from that shown in FIG. 1;

FIG. 3 is a top plan of FIG. 2; and

FIG. 4 is a bottom plan of FIG. 2.

The right side of the bottle is the same as the left side as shown in FIG. 1.

I claim:

The ornamental design for a bottle, substantially as shown and described.
